2 Claims. (Cl. 114—56)

The present invention relates to building of vessels and boats. More particularly, the present invention relates to a hull the surface of which has a special shape, and, further, it relates to a method of designing or drawing a hull of said shape.

It is common that vessels, which are designed to be plated with metal sheets, plywood or sheets of other materials, have been shaped in such a way that the frames are designed using straight lines, in order to make it possible to carry out the plating work using single curved sheets instead of double curved sheets. This makes the plating work easier, of course, but has the drawback that the shape of the vessel becomes less nice looking and ungainly. These hull shapes are very common, especially in connection with small wrapped plane bottom vessels or the so-called V-bottom boats. When in such boats the sheets to form the bottom between the keel and the chine are bent, said sheets have the tendency to take a convex or concave frame shape, although the bottom part of the boat has been shaped with straight frame lines. This tendency has been used by many boat builders in order to get soft bottom lines. The side surfaces, i.e. the surfaces between the railing and the chine at the most are liked to be shaped using concave frame lines. So far, however, one has not succeeded in sheathing side surfaces having concave frame shapes using single curved whole or monolithic plates or sheets. Therefore such boats having concave frame shapes of the side surfaces are plated either using slender planks or double curved sheets and plates as for instance in the common ships building. Previously tests have been made in order to compose hull surfaces using elements forming parts of cylinders and cones, however, without any practical success.

From the geometry there are known curved surfaces of such a kind that through a point located in the surface a straight line can be drawn, which completely is included into said surface. This invention makes use of this property for the forming of hulls for boats and ships in such a way that also concave or convex side surfaces can be plated using single curved plates, although the frame lines are curved according to a chosen curvature. One of the advantages connected to this invention is the bigger freedom the designer has when forming the hull instead of the previous method using straight frame lines. In the following description the sentence frame section means a plane, which in the usual manner is in a 90° angle at both the water line planes and the centre plane, the latter being the vertical plane along the keel line. The used expression double curved surface indicates a surface of such a shape as for instance a sphere, while the cylinder for instance represents a single curved surface. The frame line, of course, is the intersectional line between the frame plane and the hull surface. One of the embodiments of the invention consequently is a hull surface, preferably the whole hull side, which is of such a shape that it intersects the frame planes in curved lines. Additionally it is bent to connect to the curved railing line and chine in the length direction of the vessel over straight lines included in the hull surface, which is single curved according to said intersectional lines between the hull surface and the frame

2

planes, and which straight lines have an inclination in relation to the frame planes depending upon the curvature of the railing line and the chine.

Another aim of the invention is also to disclose a method to be used in the designing work in order to determine said inclined straight lines in such a way that they are laying in the single curved hull surface chosen according to the frame curvature. The intersectional points of the straight lines with the railing line and the chine thereafter can be correctly marked on the hull side plate or sheet and this thereafter easily can be bent over these straight lines to connect with the railing line and the chine. A single whole or monolithic side sheathing formed according to this method therefore as a matter of fact easily can be formed as a single curved surface in spite of the curved frame line, which makes the work at the shipyard considerably easier than before.

In the following description there is disclosed more in detail an embodiment of the invention, thus disclosing how the design work can be carried out in order to fix the location of the straight lines laying in the hull side and over or along which the hull plate, in spite of the curved frame line, has to be bent in order to get the sheet single curved across the direction of said lines. As an example there has been chosen the side of a V-bottom boat.

In order that the present invention may be readily carried into effect, it will now be described with reference to the accompanying drawing, wherein:

FIG. 1 is a side view of an embodiment of the hull surface of the present invention;

FIG. 2 is a bottom view of the embodiment of FIG. 1;
FIG. 3 is a front view of the embodiment of FIG. 1.

In designing the hull, the designer selects, as usual, the desired curvature of the frame line, and must then fix different points of the straight lines between the railing and the chine, over which lines the hull plate has to be bent. Some of these lines have been marked on the drawing in using the marking 1_1 to 1_{20} . The hull consequently has to be formed in such a way that from the railing always can be drawn against the frame planes inclined straight lines, for instance the lines 1_1 to 1_{20} , which are laying in the hull surface. According to this method a plate of plywood sheet can be bent to the hull shape along the bending lines 1_1 to 1_{20} without becoming double curved.

The geometrical condition for a straight line to be included in the hull surface is that the distance from an intersectional point on the straight line with an assumed water line of the hull surface has the same distance from the centre plane $f-g$ in FIG. 2 as well as in FIG. 3. In order to determine the hull shape with a sufficient accuracy for ships building, it is enough to determine the intersectional lines of the hull with a relatively small number of frame and water lines. In the drawing there has been determined the intersectional lines of the hull with the frame planes $0-9$ and the water line planes $w1_1$ to $w1_4$. When designing the hull shape of the boat, the frame lines and water lines are adapted to each other in the common way. In order to get the hull shape to meet the requirements according to this invention the inclined straight lines 1_1 to 1_{20} have to be adjusted to the frame lines as well as to the water lines. In this case all the straight lines 1_1 to 1_{20} have been adjusted to the frame lines $0-9$ and the water lines $w1_1$ to $w1_4$ in the same way as the line 1_{18} chosen as an example. The distance h from the centre plane $f-g$ to the intersectional point c (located in the water line plane) between 1_{18} and $w1_3$ is the same in FIG. 2 and FIG. 3. This means that the point c is laying in the hull surface. In the same way the distance of the intersectional point b of the line 1_{18} and $w1_4$ from the centre plane $f-g$ is the same in FIG. 2 and FIG. 3. When the line 1_{18} crosses the railing line and the chine, and when for instance the two therebetween located points b

and c lie in the hull surface, the whole line 1_{18} lies in the hull surface completely to meet all practical requirements. In the same manner all the other straight lines 1_1 to 1_{20} have been adapted both to the frame lines $0-9$ as well as to the water lines $w1_1$ to $w1_4$, and consequently all these lines are included to their whole length in the hull surface. A further control measure in order to get assured that for instance the point c will be in the hull surface consists therein that the point c is laying on the same drawn vertical line $c-c$ between FIG. 1 and FIG. 2. Just in the same way the intersectional point b and all other intersectional points between the other lines 1_1 to 1_{20} and the water lines $w1_1$ to $w1_4$ are on the corresponding vertical lines between FIG. 1 and FIG. 2.

Apart from the above the adapting of the frame lines $0-9$, water lines $w1_1$ to $w1_4$ and the lines 1_1 to 1_{20} to each other can be managed in such a way that the angles α_1 to α_{20} continuously change, these angles being those under which the extensions of the lines 1_1 to 1_{20} are crossing an arbitrary line $i-j$. This has been made in the same manner for all the lines 1_1 to 1_{20} as for the line 1_{18} . From the intersectional point k between the extension of the line 1_{18} with the line $i-j$ there has been determined a perpendicular distance $k-l$, which chosen in a convenient length measure, for instance millimetres, numerically corresponds to the degree number of the angle α_{18} . The same operation preferably to be carried out at the fore, mid and stern part of the hull. Through the points determined in this way it is possible to draw a curve $m-n$, which discloses that the angles between the lines 1_1 to 1_{20} and the frame planes continuously and smoothly change.

On the other hand, if towards the line $i-j$ a perpendicular line is drawn, the part being between the line $i-j$ and the curve $m-n$, for instance the part $k-l$, numerically indicates the degree figure of the corresponding angle of inclination e.g. α_{18} against the frame planes i.e. the angle of the straight line, e.g. 1_{18} , which is laying in the hull surface and the extension of which crosses the line $i-j$ in its intersectional point with for instance the line $k-l$. In this way the location of for instance the line 1_{18} easily can be determined in such a way that from a point o on the line $i-j$ the perpendicular distance $o-p$ is measured, whereafter the angle α_{18} , the degree number of which numerically corresponds to the distance $o-p$, will be drawn through the point o . In the same way consequently an indefinite number of inclined straight lines can be drawn close to each other through each point of the hull surface so that said lines surely are included in the hull surface, which on the other hand means that in the whole surface there

are included straight lines from the railing to the chine and which, as said, are laying in the hull surface. Because of that the hull surface as a whole can be bent over said straight bending-lines. This also means that the hull surface completely can be sheathed using a sole single curved sheet from the fore part to the stern part of the boat.

It is understood that the hull need not necessarily be completely shaped according to the invention and, consequently, if desired only certain parts of the hull surface, such as, for example, the fore part of a ship, may be shaped according to the invention.

What is claimed as new and desired to be secured by Letters Patent is:

1. A hull surface having a bow portion, a stern portion and a keel portion extending from said bow portion to said stern portion, a center plane extending substantially vertically through said keel portion, a plurality of frame planes intersecting said center plane at right angles, a chine and a railing, said hull surface comprising a single curved surface including a plurality of straight lines wholly within said curved surface extending from said chine to said railing at an inclination to said frame planes, said single curved surface intersecting said frame planes in curved lines and being bent at said plurality of straight lines to connect said chine with said rail.

2. A hull surface having a bow portion, a stern portion and a keel portion extending from said bow portion to said stern portion, a center plane extending substantially vertically through said keel portion and a plurality of frame planes intersecting said center plane at right angles, said hull surface comprising a single curved surface including a plurality of straight lines wholly within said curved surface at an inclination to said frame planes, said single curved surface intersecting said frame planes in curved lines and being bent at said plurality of straight lines.
